UNITED STATES PATENT OFFICE.

LUKE P. V. WILLIAMS, OF WHITELAND, INDIANA.

SIGNAL DEVICE FOR RAILROAD-CROSSINGS.

1,394,385.

Specification of Letters Patent.

Patented Oct. 18, 1921.

Application filed May 23, 1921. Serial No. 471,841.

To all whom it may concern:

Be it known that I, LUKE P. V. WILLIAMS, a citizen of the United States, residing at Whiteland, in the county of Johnson and 5 State of Indiana, have invented certain new and useful Improvements in Signal Devices for Railroad-Crossings; and I do hereby declare the following to be a full, clear, and exact description of the invention, such as 10 will enable others skilled in the art to which it appertains to make and use the same.

The present invention relates to signal mechanisms for use at grade crossings or other dangerous points of railroad tracks, 15 and aims to provide a novel and improved apparatus for giving signals or indications at the crossing or other point of a track when a train or car approaches the crossing or point, in order to warn persons about to 20 cross the track.

A further object is the provision of such an apparatus which will give a signal or indication to the effect that a train or car is approaching, and which will give another 25 signal or indication to the effect that the train or car is leaving, when the train or car approaches and leaves the crossing or protected point, respectively, in order that the signal device will indicate whether the 30 train or car is coming or going.

Another object is the provision of a signal mechanism having means whereby the approach of a train or car will set a corresponding signal member to indicate such 35 condition, means whereby said signal member is restored to normal when the train or car has reached the crossing or protected point and another signal member operated to indicate that the train or car is leaving, 40 and means operable for the restoration of the second named signal member when the train or car has gone a predetermined distance beyond the crossing or protected point.

45 It is also an object of the invention to provide such a mechanism which is comparatively simple and inexpensive in the construction and installation, and which will operate in a practical and efficient manner.

50 With the foregoing and other objects in view, which will be understood as the description proceeds, the invention resides in the construction and arrangement of parts, as hereinafter described and claimed, it being understood that changes can be made 55 within the scope of what is claimed, with-

out departing from the spirit of the invention.

The invention is illustrated in the accompanying drawings, wherein:—

Figure 1 is a diagrammatical view of the apparatus.

Fig. 2 is an elevation of one of the signal devices, showing one signal arm or member raised and the other down in normal position.

Fig. 3 is a view of such signal device showing one arm raised and in section, and illustrating the electrical circuits in diagram.

As shown in Fig. 1, the signal apparatus is duplicated at the opposite sides of the track, with the two mechanisms in reversed positions, for two-way traffic, in both directions, but such duplication is unnecessary 75 with one-way traffic, or the two mechanisms can be used on double tracks as will be obvious to those versed in the art.

Each apparatus includes a signal device including a post 7 at one side of the track at 80 the crossing or protected point, and a pair of signal arms or members 8 and 9 pivoted, as at 10, on the post 7 to swing upwardly and downwardly to and from signaling position. As shown, said signal members are 85 located at opposite sides of the post 7, and contain suitable legends, such as "Train coming" and "Gone" or the like, for giving signals or indications to the effect that a train or car is approaching or is leaving, respectively, according to which signal member is raised.

In order to move said signal members to and from signaling position, they have the arms 11 projecting from the pivot 10 and 95 connected by links 12 with cores or plungers 13 working in the respective solenoids 14 and 15 carried by the post 7. The cores 13 are raised when the signal members swing downwardly or drop to normal position and 100 when either solenoid or electro-magnet is energized, it will attract the corresponding core downwardly into it, thereby swinging the corresponding signal member upwardly.

The signal members are preferably hollow, as seen in Fig. 3, to contain an electric lamp 16 for illuminating the signs thereon, and the lamp 16 is disposed in an electrical circuit 17 including a battery 18 or other source of electrical energy. Such circuit includes a contact 19 carried by the signal member and a contact 20 carried by the

post 7 to engage one another when the signal member is raised, so as to close the circuit of the lamp 16, and to illuminate the signal member, especially at night.

5 In addition to a visual signal or indication, an audible signal or alarm can be given, such as by means of an electric bell 21, which can be mounted on the post 7. The bell is connected in a shunt with the 10 circuit 17 across the contacts 19 and 20, and the shunt includes a contact 23 carried by the signal member and a contact 24 carried by the post, to engage one another when the signal member is raised, thereby the bell 21 15 is energized simultaneously with the lamp 16, to provide the combined visual and audible signals.

In order to operate the signal member 8 when a train or car approaches the crossing, a normally open switch 27 is located a suitable distance from the crossing adjacent to the track to be moved against a contact 28 when the train approaches within a predetermined distance of the crossing, to 25 close an electrical circuit including the contact 28, conductor 29, battery 30 or other source of electrical energy, conductor 33, electro-magnet 32, conductor 31 and switch 27 when closed. The approach of the train, 30 in closing the switch 27, will therefore energize the magnet 32 which attracts an armature switch 34 against a contact 35, to thereby close another electrical circuit including the contact 35, conductor 36, solenoid 14, 35 conductor 38, contact 39, a switch 40 located near the crossing, another contact 41 normally engaged by the switch 40, a conductor 42, the magnet 32, conductor 33, battery 30, conductor 37 and the switch 34. The magnet 32 in closing the switch 34, will therefore 40 close the circuit of the solenoid 14, which being energized will raise the signal member 8 to indicate the approach of a train. Such circuit of the solenoid 14 includes the normally closed switch 40, which is located 45 near the crossing, preferably at that side opposite to the switch 27, and said switch 40 is arranged to be opened when the train or car passes the crossing, whereby the opening 50 of the circuit of the solenoid 14, will de-energize said solenoid, resulting in the signal member 8 swinging down to normal position. The switch 40 is a double switch, and when moved to open the circuit of the 55 solenoid 14, it is brought against a pair of contacts 43 and 45 to close another circuit including the contact 43, battery 30, conductor 48, an electro-magnet 47, conductor 46, contact 45 and switch 40. The magnet 60 47 when energized will attract an armature switch 49 against a contact 50, thereby closing a circuit including the contact 50, conductor 51, solenoid 15, conductor 54, a normally closed switch 55 at a distance from the 65 crossing, contact 56 normally engaged by the

switch 55, conductor 57, magnet 47, conductor 48, battery 30, conductor 53, and switch 49. The solenoid 15 is therefore energized to raise the signal member 9, and the magnet 47 is kept energized to hold the switch 49 closed. Such circuit is opened, however, when the train has moved a predetermined distance beyond the crossing, where the switch 55 is located, said switch being arranged to be opened by the train, thereby 70 opening the circuit of the solenoid 15, and the signal member 9 therefore drops to normal position. The switches 27 and 55 are located suitable distances from the crossing 75 in opposite directions therefrom for operation by the train in approaching and leaving the crossing, respectively.

The switches 27, 40 and 55 have wiper arms 58 past which the car wheels or a tripping member 59 on the train or car is 80 movable, for operating said switches.

With the apparatus as shown and described, supposing that a train or car is approaching the crossing from the right to the left in the direction of the arrow 25 in Fig. 90 1, when the train approaches the crossing within a predetermined distance (several hundred yards in practice), the tripping member 59 in passing the switch 27, will close said switch, thereby closing the circuit of the magnet 32 which will close the switch 34 and energize the solenoid 14, thereby raising the signal member 8 to indicate the approach of the train. The magnet 32 is also in the circuit of the solenoid 14 95 and switch 40, to keep the signal member 9 raised until the train reaches and passes the crossing, in which event the tripping member 59 will move the switch 40 away from the contacts 39 and 41 against the 100 contacts 43 and 45. This will open the circuit of the solenoid 14 and magnet 32, the switch 27 having been opened by itself after release by the member 59. The solenoid 14 and magnet 32 are therefore deenergized, 110 and the signal member 8 will swing down. The switch 40, at the same time, closes the circuit of the magnet 47, and said magnet 115 closes the switch 49, which in turn closes the circuit of the solenoid 15, including the switch 55 and magnet 47. The magnet 47 is kept energized to maintain the solenoid 15 energized, and to support the signal member 9 in signaling position, to indicate the fact that the train is leaving the crossing or has gone. When the train has moved a predetermined distance beyond the crossing, the member 59 opens the switch 55, thereby opening the circuit of the solenoid 15 and magnet 47, the switch 40 having previously 120 returned to normal position, so that said magnet and solenoid are deenergized and the signal member returned to normal position. The switches are all spring or gravity actuated to return to normal position.

tion when released. In this manner, separate and distinct signals or indications are given when a train approaches and leaves the crossing, to give the desired warnings 5 to those approaching the crossing.

When the train or car approaches the crossing from the opposite direction, or in the direction of the arrow 26 in Fig. 1, the member 59 will be at the opposite side of the 10 track, to operate the switches 27, 40 and 55 of the other apparatus, which may also be taken to represent an apparatus of another track, when double tracks are used. The operation is precisely the same as above 15 described.

The apparatus is entirely automatic, to eliminate the necessity for a watchman at the crossing, and to give appropriate signals whereby accidents are avoided.

20 Whenever one of the signal members is raised or swung to signaling position, the circuits of the corresponding lamp 16 and the bell 21 are closed, and a common battery and bell can be used for all of the 25 circuits of the signal members as will be obvious to those versed in the art.

Having thus described the invention, what is claimed as new is:—

1. A signal mechanism including a signal 30 device having means for signaling the approach of a train and means for signaling the fact that the train is leaving, and means operated by the train when approaching from a distance to bring the first named 35 means to signaling position, and operable when near said device for changing said device to bring the second named means to signaling position, and operable when the train has moved a distance from said device 40 for restoring said device.

2. A signal mechanism including a signal device having two signal members, one to indicate the approach of a train and the other to indicate that the train is leaving, 45 means controlling the first named signal member and operable by a train approaching said device from a distance for moving said first named signal member to signaling position, means controlling both signal members and operable when the train is near said device 50 so that the first named signal member is restored and the second named signal member moved to signaling position, and means controlling the second named signal member and operable by the train when it has moved a distance beyond said device for restoring the second named member.

3. A signal mechanism including a signal device having means for indicating the approach of a train and means for indicating that the train is leaving, and electrical apparatus controlling said device and including a member to be operated by a train ap-

proaching from a distance for controlling said device to bring the first named means 65 into signaling position, a member operable by the train when it is near said device for restoring the first named means and bringing the second named means to signaling position, and a member operable by the train 70 at a distance when leaving said device for restoring the second named means.

4. A signal mechanism comprising a signal device having two signal members, one to indicate the approach of a train and the other to indicate that the train is leaving, 75 an electrical means for each of said members to move same to signaling position, and electrical circuits and controlling means for said electrical means for control by a train approaching from a distance to control one of 80 said electrical means for moving the first named signal member to signaling position, and controlled when the train is near said device for controlling both of said electrical 85 means to restore the first named signal member and move the second named signal member to signaling position, and controlled by the train when leaving the signal device for restoring the second named signal member. 90

5. A signal mechanism comprising a signal device having two signal members, one to indicate the approach of a train and the other to indicate that the train is leaving, 95 electrical means for each of said members for moving same to signaling position, means operable when a train approaches from a distance for energizing one of said electrical means to move the first named member to signaling position, means operable when the train is near said device for opening the circuit of said electrical means 100 to restore the first named signal member and to simultaneously operate to energize the other electrical means for moving the second named signal member to signaling position, and means operable when the train is leaving for opening the circuit of the second named electrical means to restore the second named signal member. 110

6. A signal mechanism including a signal device having means for indicating the approach of a train and means to indicate when the train is leaving, and devices controlling said signal device by the approach, passing 115 and leaving of a train to set said signal device accordingly, to indicate when the train is approaching and leaving.

In testimony whereof I have signed my name to this specification in the presence of 120 two subscribing witnesses.
